JAMES SPEED, OF MITTINEAGUE, MASSACHUSETTS.

WATERMARKING APPARATUS FOR PAPER-MACHINES.

1,119,730.

Specification of Letters Patent.

Patented Dec. 1, 1914.

Application filed April 13, 1912. Serial No. 690,515.

To all whom it may concern:

Be it known that I, JAMES SPEED, a citizen of the United States of America, and resident of Mittineague, West Springfield, in the county of Hampden and State of Massachusetts, have invented certain new and useful Improvements in Watermarking Apparatuses for Paper-Machines, of which the following is a full, clear, and exact description.

This invention relates to means for the water-marking of paper in the process of manufacture, which instead of being employed on the wet portion of the machine, where the dandy roll has been usually located, and instead of being structurally like a dandy roll, is employed in conjunction with, and adjacent to, some one of the steam drums of the drier forward of the paper machine, and has the nature of a device for impressing or indenting in the partially dry, yet still moist, web, the letters, design or configuration which may be produced by an electrotypes, stereotype, or engraving.

The apparatus comprises companion cylinders one of which is yieldingly movable relatively to the other, one cylinder carrying one or more watermarking members projecting from the periphery thereof, having an arc shaped impression forming face, and both cylinders comprising circular and circumferentially continuous coacting portions or members which are of frusto-conical form and adapted for maintaining the pair of cylinders in the proper degree of separation and so that when a pair of such frusto-conical parts or members are axially adjusted relatively to another pair of the correspondingly shaped members, the degree of normal separation of the pair of cylinders may be varied, as is desirable in cases when at different times paper webs of different thicknesses are being run, or where the depth of the impression or "watermarking" in the paper is desired to be varied.

The invention is described in conjunction with the accompanying drawings and is set forth in the claims.

In the drawings:—Figure 1 shows the watermarking apparatus in sectional elevation in relation to some of the steam drums of the paper drier. Fig. 2 is an elevation as seen at right angles to Fig. 1, the drier drums not being shown. Fig. 3 is a partial

sectional elevation showing parts included in Fig. 1, but having different positions from those represented in such figure. Fig. 4 is a partial sectional elevation, on a larger scale, as seen beyond the line 4—4, Fig. 2.

In the drawings, 10, 12 and 13 represent the first, second and third drums of a series comprised in the steam drier; and α represents the web of paper being drawn to the rightward from the paper machine and having its course through the drums, and which after passing through one or more of the drums and becoming partially dry and susceptible of receiving, while in a still damp condition, the watermarking impressions, has a detour course as indicated in Fig. 1, between the pair of cylinders A and B. These cylinders A and B are located between opposite uprights D D comprised in the supporting frame therefor in which are vertical recesses α in which are fitted journal boxes b and d , those b for the lower cylinder being immovable, while those d for the upper cylinder are so fitted as to have free sliding movements vertically as guided in the recesses α . The upper cylinder has one or more projections f extending radially from its periphery, each provided with an arc shaped impression forming face. The upper boxes d have upwardly extending stems g guided through the cap plates i of the frame uprights, coacting with which are the weighted pivoted levers F to give pressure downwardly through the stems to the upper boxes and to the upper cylinder B.

The cylinders A and B are to be rotated at uniform speed corresponding to the travel of the paper web, which passes between them, in any suitable manner, as, for instance by power transmitted to shaft K through gearing K^2 , K^3 , L and L^2 .

One of the cylinders has circular and circumferentially continuous parts u of frusto-conical form, and the other cylinder has for coaction with such frusto-conical parts, members or parts u^2 , u^3 , also of frusto-conical form, one pair of such members being essentially axially adjustable. As considered most practicable, both sets of the frusto-conical parts are provided as separately formed collars having their edges so beveled that the edges of those which are in contact with each other are in reversed convergence, although the convergence of the bevel edges of both the collars on each

cylinder are in the same direction. The frusto-conical shaped collars may be secured in any manifest or practicable manner, as, for instance, by having hubs u^3 through 5 which binding screws u^4 are applied for engagement against the arbor, or journal extensions of the cylinder.

By loosening the binding screws u^4 for a set of the frusto-conical shaped collars app-10 pertenant to one of the cylinders and moving them both uniformly axially in the same direction, the degree of separation of the pair of cylinders may be variably effected to a nicety.

15 In this class of apparatus it is desirable to bodily endwise adjust the cylinder having the watermarking projections f so that the watermarking impressions may be positioned at the proper places in the width of 20 the sheet or relatively to the margins of the web so that in the subsequent slitting of the web and cutting into sheets the locations of the marks in the subdivisions of the paper may be as desired. And, therefore, the apparatus comprises means for the axial adjustment of the watermarking cylinder, the same consisting of the screws v horizontally threading through the yoke shaped brackets w outside of the frame uprights d , 25 which have forcing engagements against the ends of the arbor or journals of the cylinder, so that by turning one of the screws outwardly and the other inwardly through its bracket, the cylinder may be easily and 30 accurately positioned. This same cylinder adjusting means may be effective for causing the transverse sliding of one set of the frusto-conical parts or members across the periphery of the other set for acquiring the 35 adjusted degree of separation of the cylinders which may be required to accord with any particular working conditions; and in view of the requirement or desirability that the apparatus shall have the capability of 40 the bodily axial adjustment of one of the cylinders for the purpose hereinabove set forth, it becomes necessary that at least one set of the frusto-conical shaped parts shall be axially adjustable relatively to the cylinder 45 of which they are an appurtenance.

I claim:—

1. In an apparatus of the character de-50 scribed, the combination with the drier drums of a paper machine, of a pair of cylinders located adjacent one of the drums, one thereof having journal bearings adapted

for movements away from the other cylinder, one cylinder being provided with a watermarking member projecting from the periphery thereof having an arc shaped im-60 pression forming face, one of the cylinders having circular and circumferentially continuous parts of frusto-conical form, and the other cylinder having, for coaction with such frusto-conical parts, circular members 65 also of frusto conical form and axially adjustable, and means for imparting a constant yielding pressure to the movable cylinder in a direction toward the companion cylinder. 70

2. The combination with the drier drums of a paper machine of an adjacently located pair of cylinders, one thereof being mounted in fixed bearings and the other having movable bearings therefor, one of the cylinders 75 being provided with an arc faced watermarking member projecting from the periphery thereof, one of the cylinders having circular and circumferentially continuous parts of frusto-conical form and the other 80 cylinder having, for coaction with such frusto-conical parts, circular members also of frusto-conical form, means for imparting a constant yielding pressure to the movable cylinder in a direction toward the companion cylinder, and means for imparting an endwise adjusting movement to one of the cylinders. 85

3. The combination with the drier drums of a paper machine of an adjacently located lower cylinder mounted in fixed bearings and a cylinder having appurtenant thereto portions or members of frusto-conical form, an upper cylinder, and vertically movable bearing supports therefor,—said upper cylinder 90 being provided with a member projecting from its periphery formed with an arc shaped impression forming face, and also provided with frusto-conical members, peripherally coacting with the first named 95 frusto-conical members,—the frusto-conical members appurtenant to one of the cylinders being axially adjustable, and means for imparting a downward pressure to said upper cylinder. 100 105
